CLAIM

The ornamental design for a payment terminal, as shown and described.

DESCRIPTION

FIG. 1 is a front, left side, and top perspective view of a payment terminal showing the new design;

FIG. 2 is rear, right side, and top perspective view thereof;
FIG. 3 is a front elevation view of the first shown embodiment;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawings are included to show portions that form no part of the claimed design.
